UNITED STATES PATENT OFFICE.

JOHN MATSON AND JAMES C. MATSON, OF BROOKVILLE, PENNSYLVANIA.

CHURN.

SPECIFICATION forming part of Letters Patent No. 316,988, dated May 5, 1885.

Application filed November 12, 1884. (No model.)

To all whom it may concern:

Be it known that we, JOHN MATSON and J. C. MATSON, citizens of the United States, residing at Brookville, in the county of Jefferson and State of Pennsylvania, have invented 5 certain new and useful Improvements in Churns; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The object of this improvement is to increase the efficiency of concentric dasher-frame churns by providing the same with features of construction that will enable the dasher-shaft and frames to be conveniently removed 20 from the barrel of the churn, and the parts entirely disconnected from each other for the purpose of being thoroughly scalded and cleaned, and thus be kept in more perfect order than is otherwise practicable. These results 25 are attained by the mechanism illustrated in the drawings herewith filed as part hereof, in which the same letters of reference denote the same parts in the different views.

Figure 1 is a side elevation, partly in section, representing a churn embodying the features of our improvement. Fig. 2 is a view 30 as seen from the top of the lid, with some of the parts cut away for the purpose of more fully illustrating features of construction and 35 their relative position. Fig. 3 is a vertical section as seen from the side opposite to that shown in Fig. 1.

A is the churn-barrel, centrally secured to the bottom of which is a metal socket or shaft-bearing, a.

40 B is the dasher-shaft, to be made preferably of hard close-grained wood, and provided at its lower end with a flanged metal thimble, B', having a reduced extension fitting the 45 socket a, as shown in Fig. 1, and secured to the shaft B by a transverse pin, b, which causes the thimble to turn with the shaft and prevent it from being worn by contact with the socket a.

C are transverse pieces and C' are vertical pieces composing the inner dasher-frame. 50 The parts C C have enlargements c c, perfo-

rated to fit closely over the shaft B, to which they are rigidly secured in the positions shown by means of ordinary wood-screws, c' c'. The vertical pieces or dasher-blades C' C' are 55 halved or matched to the ends of the transverse parts C C, and secured in position by screws c' c'.

D D' are transverse pieces and D' D' are vertical pieces composing the outer dasher-frame, and are connected at their ends, as shown at d', in the same manner as the parts C C'. The lower piece, D, of the outer frame has an enlargement, d, perforated to fit loosely over the shaft B, and the piece D' has an enlargement, d', perforated to fit closely around 60 a sleeve, E', or reduced extension from the hub of the bevel-gear E, which meshes with a corresponding gear, F, secured to a horizontal shaft, f, supported by a pillow-block, F', and 65 provided at its outer end with a momentum-wheel having a crank or operating-handle, f'. The gear F is secured to the shaft f by a set-screw, g.

G is a bevel-gear secured to shaft B by set-screw g' in position to mesh with the gear F.

H H' represent the churn-lid, divided at the center into two equal parts, hinged together at one side, as shown at h, and provided in the center with semicircular recesses to fit 80 around the extension E' of the gear E.

I I are metal plates secured to the churn-lid by wood-screws, i, and flanged downward, as shown at I' I', and provided with thumb-screws I' I' for securing the lid to the churn-barrel.

K is a spring secured to the churn-lid H by wood-screw k', and provided at its other end with an inward extension, as shown at K', which springs over the downward extension 90 I' of the plate I and holds the parts H H' of the churn-lid together.

J is a spring curved to fit the sleeve or reduced extension E' of the gear E, and is secured to the lid-half H' by means of a twisted 95 end, as shown at J', in a suitable position to make the curved end J bear against the sleeve E' with sufficient tension to hold the shaft B and gearing E G in position to mesh with the gear E. The upper edge of the spring J engages with the hub of the gear E, and operates as a bearing for the same, and prevents the 100

churn-lid from being worn by contact therewith. The thimble B' at the lower end of the shaft B prevents the latter from wearing away, and also operates as a support for holding the outer dasher-frame in proper relative position with the gear E.

By reason of the lid H H' being arranged to open in the center the dasher-shaft and connecting-frames may be easily removed from the churn-barrel, after which the parts may be disconnected from the shaft B and from each other and thoroughly scalded for the purpose of keeping the same in perfect order.

Motion given to the mechanism through the driving-shaft f and gear F will operate the dasher-blades in opposite directions, as in all churning having concentric dashers.

Having explained the construction and op-

eration of our improvement, what we claim as new, and desire to secure by Letters Patent, 20 is—

The churn-lid composed of the hinged parts H H', provided with gear-wheel F, springs J and K K', and plates I I', having thumbscrews I², in combination with geared shaft B 25 and concentric dasher-frames, all constructed and arranged to operate substantially as and for the purpose set forth.

In testimony whereof we affix our signatures in presence of two witnesses:

JOHN MATSON,
JAMES C. MATSON.
